UNITED STATES PATENT OFFICE

2,436,455

INKING MECHANISM

Frederick W. Seybold, Westfield, N. J., assignor to
 American Type Founders, Incorporated, Elizabeth, N. J., a corporation of New Jersey

Application March 8, 1944, Serial No. 525,560

14 Claims. (Cl. 101—350)

1

This invention relates to printing presses and the like and more particularly to inking mechanisms or similar liquid distributing devices adapted to be used in connection with such presses.

The general object of the invention is the provision of a novel and improved device of the class described for the efficient transfer and thorough mixing of the ink in the course of its passage from the reservoir or fountain to the printing form. The embodiment of the invention, which has been selected for exemplary disclosure herein is particularly adapted for application to a bed and cylinder press, for example, the well-known Kelly press.

The invention in its preferred embodiment contemplates the provision of a primary ductor roller arranged to oscillate to and from contact with the fountain roller and a second ductor roller arranged to oscillate to and from contact with the first roller or ink drum of the usual train of inking and distributing rollers adjacent the path of the form or printing plate. Between the two ductor rollers there is disposed a set of continuously rotating working rollers which may include a vibratory roller, for example, of the McKinley type. This intermediate group of rollers is adapted to be intermediately contacted by the ductor rollers and is designed to thoroughly triturate or "cut up" the ink preparatory to applying it to the pyramidal system of inking and distributing rollers. With this arrangement a particle of ink travels almost twice as far as in the ordinary press of this type before it reaches its destination on the form; in other words, the "inches of distribution" are more than doubled.

Another feature which characterizes the invention resides in the use of the McKinley distributing roller in the intermediate set of rollers. This relieves the operator of the necessity of closely setting the fountain keys for maintaining an even color, since the laterally oscillating McKinley roller serves to spread the ink from the heavier areas to the lean areas.

More particular features of the invention involve the novel and advantageous means for mounting the two ductor rollers to swing about the same pivot point, and for interrupting the movement of the rollers when the impression is thrown off, either automatically by the detection of the misfeeding of a sheet or positively by manual means under the control of the operator.

A still further object of the invention is the provision of novel details of construction of the liquid transferring mechanism, such as the re-

2

silient mounting of the ductor roller bearing brackets to provide sufficient cushioning of contact of the rollers with the fountain and liquid receiving drums or rollers, and to adapt the roller supports to the particular mounting and operation of the interrupter devices.

Other objects and features of novelty will be apparent from the following specification when read in connection with the accompanying drawings in which one embodiment of the invention is illustrated by way of example.

In the drawings,

Figure 1 is a fragmentary view in side elevation of a bed and cylinder printing press to which my invention has been applied; parts of the press frame being broken away for better illustration of certain portions of the mechanism;

Figure 2 is a fragmentary plan view of the inking mechanism showing the mountings of the ductor rollers at the near side of the press as viewed in Figure 1;

Figure 3 is a vertical sectional view through the bearing brackets of one of the ductor rollers, taken substantially on line 3—3 of Figure 2;

Figure 4 is a horizontal sectional view taken on line 4—4 of Figure 3 and passing through one of the brackets;

Figure 5 is a transverse vertical sectional view through the adjacent brackets taken substantially on line 5—5 of Figure 3;

Figure 6 is a fragmentary horizontal sectional view through the actuating shafts for the interrupter fingers which are adapted to limit the oscillation of the ductor rollers under certain conditions, the view being taken substantially on line 6—6 of Figure 3; and

Figure 7 is a fragmentary transverse sectional view through the vibrating roller forming a part of the intermediate set of working rollers.

A practical embodiment of the invention has been illustrated in the drawings accompanying the present specification and will be described in detail herein as applied to a Kelly press of the bed cylinder type, such as for example as

illustrated in the Kelly Patent 1,700,680 of January 29, 1929. The printing parts of this press and the ink distributing devices will be recognized and their functions clearly understood by those skilled in the art. In Figures 1 and 2 of the drawings, the main frame of the press is designated by the reference numeral 10 and it will be seen that side portions of this frame are extended upwardly as at 11 to support the bearings 12 of the impression cylinder shaft 13. The bed of the press (not shown) is adapted to re-

ciprocate horizontally with the printing face of the form or plate in the plane indicated by the line X—X. A substantially conventional pyramidal bank of inking rollers is designated generally by the reference numeral 15 and comprises the three inking rollers 16 which contact with the form, and the distributing rollers 17, certain of which may be of the oscillating type and contact with the three inking rollers 16. A roller of smaller diameter indicated at 18 contacts with one of the distributing rollers 17 and also with the transfer roller or drum 20. All of these rollers are driven by suitable or conventional means operatively connected with the power means for driving the press.

At the right hand end of the press as viewed in Figure 1 an inclined bracket 22 is provided which serves to support the ink fountain 23 which comprises the end plates 24 and the fountain roller 25.

Upon each side frame of the main frame 10 of the press and at points intermediate the fountain roller 25 and the ink transfer drum or roller 20 are the supplemental side frames 26, the remote one of which is shown in Figure 1 of the drawings. These supplemental frames provide bearing support for a set 27 of intermediate working rollers and driving means therefor. The largest element of this set of rollers is the drum 30 which is mounted upon a shaft 31 rotating in the frames 26 and two distributing rollers 32 and 33 are similarly rotatably mounted in the frames and are in continuous contact with the drum 30. Also mounted in the frames 26 is the shaft 34 of the oscillatory distributing roller 35 which is preferably of the McKinley type. This roller is adapted to contact with the distributing rollers 32 and 33 and the contact pressure may be regulated by suitable means controlled by the thumb screw 36. A more or less diagrammatic showing of the McKinley roller will be seen in Figure 7 of the drawings, the shaft portion 34 of the roller being provided with the reversing grooves 37 adapted to be traversed by the crescent key 38 secured to the outer rotatable and reciprocatable working portion 40 of the roller. The construction of this roller forms no part of the present invention and is familiar to workers in this field. The contact pressure of the peripheral portion of the roller 35 against the rollers 32 and 33 causes it to rotate and to oscillate to and fro along its shaft.

Beneath the intermediate set 27 of working rollers, there is disposed a transverse rock shaft 45 which is adapted to be oscillated about its axis by suitable means, for example a cam, driven by the press drive. The shaft 45 has bearings in the side frames of the press frame 10. There are secured to the shaft 45 adjacent each end thereof, the inner and outer roller supporting brackets 46 and 47. It will be understood that the arrangement shown in Figure 2 is substantially duplicated upon either side of the press and the two inner brackets 46 serve to support the axle 48 of a primary ductor roller 50 and the outer brackets 47 serve to support the axle 51 of another ductor roller 52. The ductor roller 50 is adapted to oscillate between contact with the fountain roller 25 and the ink drum 30 of the intermediate set and the second ductor roller 52 is arranged to oscillate between the ink transfer roller or drum 20 and the ink working drum 30. Each of the brackets is provided with a forked or trough-like portion 54 which receive the ends of the shafts 48 and 51 and the shafts

5 are retained within the troughs by means of the latches 55 pivoted to their respective brackets as by means of the pins 56 and urged toward closed position by means of the springs 57 which are stretched between the ears 58 and the arms 59 on the latches. By these means the ductor rollers 50 and 52 may be readily detached from their bearing brackets for renewal or access to other portions of the press.

10 It will be readily understood that the rocking of the shaft 45 causes the ductor rollers 50 and 52 to oscillate, the ductor 50 serving to transfer a quantity of ink from the fountain roller 25 to the drum 30, whereupon the ink is worked up 15 by means of the rollers 32 and 33 and the oscillating McKinley roller 35. The ductor roller 52 transfers the worked ink from the drum 30 to the transfer roller 20 from which it is carried to the form. During the passage from the fountain 20 to the drum 20 the ink is thoroughly cut up and worked by the intermediate set of rollers and is also more thoroughly and evenly distributed from end to end of the rollers by means of the oscillatory roller 35. This arrangement relieves the 25 operator of the necessity of making a very close or accurate setting of the keys of the fountain 23. Of course, for certain conditions of operation, the McKinley distributing roller may be removed and one or the other distributing rollers 30 32 and 33 may be dispensed with, this providing added flexibility to the inking system.

30 The present invention also provides novel means for locking the ductor roll carrying brackets 46 and 47 to the rock shaft 45 and also provides resilient cushioning means ensuring resilient contact between the ductor rollers and the other ink carrying rollers with which they contact and providing resilient lost motion connections for cooperating with the interrupting devices to be described later. These features will 40 now be described.

A sleeve 60 is disposed within a cylindrical bore 61 formed in each of the brackets 46 and 47 and surrounds the shaft 45. Each of the sleeves 60 is secantially bored as at 62 to receive the clamping pin 63 which is arcuately cut away at one side as at 64 to conform to the curvature of the shaft 45. The clamping pin 63 extends upwardly into an enlarged bore or well 65 in the bracket and is threaded to receive the internally threaded tubular portion 66 of the elongated nut 67 having a squared portion 68 for the application of a tool to rotate the same. The lower end of the tubular sleeve portion 66 of the nut 67 bears upon the shoulder 69 formed on the sleeve 60 adjacent the bore 62, and when tightened serves to draw the clamping pin 63 upwardly to grip the shaft 45, thus locking the sleeve 60 firmly to the rock shaft.

60 However, the bracket 46, 47 still has limited rotary movement with respect to the sleeve 60 to permit a certain amount of play or lost motion to allow for variations in the diameters of the mutually contacting rollers, and this lost motion is given a resiliency by means of the pairs of springs 70 and 71. These springs are disposed within a transverse bore 73 in each of the brackets, the bores being closed after insertion of the springs and their mounting elements by means of the plugs 75. Each of the springs 70 and 71 are seated centrally in the seating elements 76 and 77, these elements being provided with vertically cylindrical faces adapted to contact with the correspondingly shaped sides of the nut element 75 67. The spring seats 76 and 77 are centered

by means of the studs or set screws 80 which are threaded through the walls of the brackets. These features are most clearly illustrated in Figures 3, 4, and 5 of the drawings. The operation will also be clearly perceived. When the ductor roller 50 is brought into contact with the fountain roller 25, the bracket 46 will be stopped although the shaft 45 may continue to rock for a slight further distance. Then the extensible pin member 63, 67 which is rigid with the shaft 45 and sleeve 60, will press the spring seat 77 toward the right in Figure 3 compressing the spring 70, and exert resilient pressure on the ductor roller 50. At the same time the opposite spring stop or seating member 76 will remain in contact with the centering screws 80. Similarly upon contact of the ductor roller 50 with the drum 30 at the limit of its opposite movement, the bracket will be stopped before the shaft 45 and the pin 67 will compress the spring 70. An exactly similar operation will take place within the brackets of the other ductor roller, and provide resilient contact with its associated ink drums 20 and 30.

Stop means are provided for preventing contact of the ductor rollers 50 and 52 with their respective fountain and inking drums although the shaft 45 may continue to oscillate. Such stop means may be automatic and controlled by interrupting devices associated with sheet detectors on the press, or they may be manually operated in order to throw out the ductor rollers when desired. Both types of stop or interrupter devices are provided by the present invention. A rock shaft 100 is suitably mounted preferably at a point beneath the fountain roller 25 and has pinned to it, adjacent each end, pairs of stop fingers 101, one finger of each of said pairs being adapted to be brought into the path of the abutment surface 102 on the ductor roller supporting brackets 46 or 47, upon rotation of the shaft 100. In Figures 1 and 3, the fingers 101 are shown in a position displaced downwardly somewhat from the abutment faces 102, but it will be readily seen that upon retraction of the roller 50 from contact with the fountain roll 25 or upon slight movement of the ductor roll 52 toward the drum 20 and away from the drum 30 the stop fingers 101 may be moved in a clockwise direction about the axis of the shaft 100 into position where upon the next return of the brackets they will abut the faces 102 and effectively limit the movement of the ductor rollers in a clockwise direction, and thus prevent the feeding of ink from the fountain roller 25 and also from the ink working drum 30. The rock shaft 100 is adapted to be operatively connected with suitable interrupter means on the press, as by means of the crank arm 104 which is fixed to the shaft 100 and is connected by means of the link 105 with interrupter devices not shown but the nature of which will be clearly understood from an inspection of the Kelly patent to which reference has been made.

For positively stopping one or more of the ductor rollers, manually operated means may be provided. In the illustrated embodiment of the invention such means are shown as applied to the brackets 46 carrying the primary ductor roller 50 only, but it is obvious that the principles of the invention may be extended to include both sets of brackets. Upon the shaft 100, which extends from one side to the other of the press, there is mounted a tubular sleeve 110 to the ends of which are secured the stop fingers 111, as by

means of the welds 110'. The operative ends of the fingers 111 are adapted to abut the faces 102 of the brackets 46. An angled strap 112 is secured to the under side of one of the fingers 111 as by means of the rivets 113, and a substantially vertical arm 115 of the strap is provided at its upwardly extending end with a handle device 116. This device consists of a tubular part 117 fixed to the arm 115 and provided with an opening for receiving the pin 118. This pin passes through the opening and also through a registering opening in the arm 115 and is surrounded by a coil spring 119 which by abutting suitable shoulders formed upon the cylinder 117 and the pin 118 serves to urge the inner pointed end 120 of the pin 118 toward engagement with one or the other of the sockets 122 or 123 which may be conveniently formed in the end plate 24 of the ink fountain 23. The knurled knob 125 is provided on the outer end of the pin 118 whereby it may be readily withdrawn from the sockets 122 and 123. The sockets or openings 122 and 123 are disposed at limiting points in the movement of the arm 115, and it will be readily seen that when the pin 118 is in engagement with the socket 122, the stop finger 111 will be dropped downwardly beyond the engaging face of the bracket into inoperative position. When pin 118 is disposed in the socket 123, the operative end of the finger 111 will abut the face 102 of the bracket and block the contact of the primary ductor roller 50 with the fountain roller 25. It will be readily observed that in Figure 1 of the drawings, the pin 118 is slightly displaced from the socket 123 in a counterclockwise direction and the finger 111 is similarly displaced from the abutment face 102.

It will be understood that various changes and modifications may be made in the embodiment illustrated and described herein without departing from the scope of the invention as defined by the following claims.

Having thus described the invention, what is claimed as new and desired to be secured by Letters Patent is:

45. 1. In a printing press or a like machine, having a supporting frame upon which are mounted a liquid fountain and fountain roller, and a roller for receiving liquid to be distributed; the combination of an intermediate set of working rollers 50 comprising a drum, a rider roller, and an axially reciprocatory roller bearing upon said rider roller, a pair of swinging ductor rollers, one adapted to oscillate between said fountain roller and said drum and the other to oscillate between said drum and said receiving roller, said ductor rollers being mounted in bearing brackets all of which have a common pivotal axis, a common actuating shaft upon which said brackets are mounted, and resiliently yielding means individually and directly connecting said brackets to said shaft to cushion the contact of said ductor rollers with those rollers which they touch.

2. In a printing press or a like machine, having a supporting frame upon which are mounted a liquid fountain and fountain roller, and a roller for receiving liquid to be distributed; the combination of an intermediate set of working rollers comprising a drum, a pair of rider rollers, and an axially reciprocatory roller bearing upon said rider rollers, a pair of swinging ductor rollers, one adapted to oscillate between said fountain roller and said drum and the other to oscillate between said drum and said receiving roller, said ductor rollers being mounted in bearing brackets, all of which have a common pivotal axis, a common

actuating shaft upon which said brackets are mounted, resiliently yielding means individually and directly connecting said brackets to said shaft to cushion the contact of said ductor rollers with those rollers which they touch, and means for individually and directly obstructing said ductor rollers for interrupting the contact of said ductor rollers with those other rollers upon occasion.

3. In a printing press or a like machine, having a supporting frame upon which are mounted a liquid fountain and fountain roller, and a roller for receiving liquid to be distributed; the combination of an intermediate set of working rollers, a pair of swinging ductor rollers, one adapted to oscillate between said fountain roller and one of said working rollers and the other to oscillate between one of said working rollers and said receiving roller, and separate movable stop abutments adapted to be brought into position to limit the swinging movement of said ductor rollers toward one of the rollers with which they normally are brought into contact, certain of said abutments being constructed and arranged for manual actuation and others for automatic actuation as when the machine is to be stopped for reasons of safety.

4. In a printing press or a like machine, having a supporting frame upon which are mounted a liquid fountain and fountain roller, and a roller for receiving liquid to be distributed; the combination of an intermediate set of working rollers, a pair of swinging ductor rollers, one adapted to oscillate between said fountain roller and one of said working rollers and the other to oscillate between one of said working rollers and said receiving roller, and movable stop abutments adapted simultaneously to be brought into position to limit the swinging movement of both of said ductor rollers toward one of the rollers with which they normally are brought into contact, means for automatically actuating said abutments upon interruption of the operation of the machine, another movable stop abutment adapted to be brought into position to limit the swinging movement of the fountain roller contacting ductor roller, and manually operable means for selectively actuating the last named abutment.

5. In a machine of the class described, a supporting frame, a pair of ductor rollers rotatably and swingingly supported in said frame and adapted to transfer liquid from one point to another in the machine, bearing brackets rotatably supporting each end of each of said ductor rollers, the bearing brackets all having a common pivotal axis, the brackets at adjacent ends of the two rollers overlapping, and a unitary stop device adapted to be brought into the paths of movement of said brackets to limit their movement in the same direction.

6. In a machine of the class described, a supporting frame, a pair of ductor rollers rotatably and swingingly supported in said frame and adapted to transfer liquid from one point to another in the machine, bearing brackets rotatably supporting each end of each of said ductor rollers, the bearing brackets all having a common pivotal axis, the brackets at adjacent ends of the two rollers overlapping, and a unitary stop device adapted to be brought into the paths of movement of said brackets to limit their movement in the same direction, said device comprising a rock shaft parallel with said rollers and carrying fingers one opposite each of said brackets, and means for rocking said shaft to bring said fingers into position to obstruct the brackets.

7. In a machine of the class described, a supporting frame, a pair of ductor rollers rotatably and swingingly supported in said frame and adapted to transfer liquid from one point to another in the machine, bearing brackets rotatably supporting each end of each of said ductor rollers, the bearing brackets all having a common pivotal axis, the brackets at adjacent ends of the two rollers overlapping, and a unitary stop device adapted to be brought into the paths of movement of said brackets to limit their movement in the same direction, and a supplemental stop device for certain of said brackets comprising a tubular sleeve rotatable on said rock shaft and carrying fingers opposite said last named brackets, and a handle connected with said last named fingers and sleeve for rocking them to and from obstructing position.

8. In a machine of the class described, a supporting frame, a pair of ductor rollers rotatably and swingingly supported in said frame and adapted to transfer liquid from one point to another in the machine, a resilient mounting for a ductor roller or the like comprising a rock shaft, a pair of bearing brackets carried by said shaft adjacent each end of said roller and rotatably receiving said roller, a bore in each of said brackets extending approximately radially of said shaft, a pin fixed to said shaft and extending through said bore, opposed springs seated in said bracket on opposite sides of said pin and adapted to bear thereagainst, whereby relative rotative movement of said bracket to said shaft is resiliently resisted.

9. In a device of the class described, a rotatable shaft, a bracket carrying said shaft, means for securing said bracket to said shaft for resiliently cushioned driving movement, said means comprising a pin secured to said shaft and extending radially therefrom through an opening in said bracket with some clearance, a pair of coil springs seated in said bracket on opposite sides of said pin and normally adapted to bear against opposite sides of the pin, centering stop means on the bracket adjacent the pin for preventing pressure of the springs on the pin beyond the central position in the direction of elongation of said springs.

10. In a device of the class described, a rotatable shaft, a bracket carrying said shaft, means for securing said bracket to said shaft for resiliently cushioned driving movement, said means comprising the sleeve inserted between said shaft and said bracket and normally relatively rotatable with respect to both, a secantial opening through said sleeve into which a portion of the periphery of said shaft projects, an opening through said bracket in substantial alignment with said secantial opening, an extensible operating pin passing through said bracket opening, fitting snugly within said secantial opening in said sleeve, and having an arcuate surface fitting the projecting peripheral portion of said shaft, a portion of said pin braced against an abutment surface on said sleeve, whereby contraction of said pin will cause the arcuate portion to grip the shaft and lock the sleeve thereto, and resilient means for centering said pin within the bracket opening whereby said bracket is resiliently urged to follow the rotative movement of said shaft in either direction.

11. In a printing press or a like machine, having a supporting frame upon which are mounted a liquid fountain and fountain roller, and a roller for receiving liquid to be distributed; the com-

bination of an intermediate set of working rollers comprising a drum, a pair of rider rollers, and an axially reciprocating roller bearing upon said rider rollers, a pair of swinging ductor rollers, one adapted to oscillate between said fountain roller and said drum and the other to oscillate between said drum and said receiving roller, said ductor rollers being mounted in bearing brackets, all of which have a common pivotal axis, means to cushion the contact of said ductor rollers with those rollers which they touch, and means for individually and directly obstructing said ductor rollers for interrupting the contact of said ductor rollers with those other rollers upon occasion, manual actuating means operatively connected with certain of said obstructing means, and automatically actuated means operatively connected with others of said obstructing means for interruption of the ductor rollers as when other parts of the machine are stopped for reasons of safety.

12. In a printing press or a like machine, having a supporting frame upon which are mounted a liquid fountain and fountain roller, and a roller for receiving liquid to be distributed; a rock shaft, means for oscillating said rock shaft about its axis, a ductor roller adapted to oscillate between said fountain roller and said receiving roller, a pair of brackets carried by said rock shaft and rotatably supporting said ductor roller, a resilient lost motion connection between at least one of said brackets and said rock shaft, and a stop abutment adapted to be moved into the path of movement of one of said brackets for preventing contact of said ductor rollers with one of the rollers with which it is adapted to be brought into contact, said lost motion connection permitting continued rocking of said shaft during the interruption to the effective operation of said ductor roller by the obstruction of said bracket.

13. In a printing press or a like machine, an oscillating printing roller installation comprising, in combination, a rock shaft, a bearing bracket for said roller, gripping means for attachment to said shaft, said gripping means including an annulus surrounding said shaft, an opening extending secantally through said annulus and intersecting the circumference of said shaft, an extensible pin having one part fitting snugly within said opening and having an arcuate surface fitting the adjacent circumferential portion of said

50

shaft, the other part of said pin abutting a shoulder on said annulus, whereby contraction of said pin will cause said arcuate portion to grip the shaft and lock the pin and annulus thereto, means for contracting said pin, and means for connecting said pin to said roller bracket, whereby rocking of said shaft will oscillate said bracket and roller.

14. In a printing press or like machine, an oscillating printing roller installation comprising, in combination, a rock shaft, a bearing bracket for said roller, gripping means for attachment to said shaft, said gripping means including an annulus surrounding said shaft, an opening extending secantally through said annulus and intersecting the circumference of said shaft, an extensible pin having one part fitting snugly within said opening and having an arcuate surface fitting the adjacent circumferential portion of said shaft, the other part of said pin abutting a shoulder on said annulus, whereby contraction of said pin will cause said arcuate portion to grip the shaft and lock the pin and annulus thereto, means for contracting said pin, and resiliently yielding means for connecting said pin to said roller bracket, whereby rocking of said shaft will oscillate said bracket and roller and the roller will be cushioned upon contact with other operative parts during operation.
